US00D881204S

(12) **United States Design Patent** (10) Patent No.: **US D881,204 S**
 Jaini et al. (45) Date of Patent: ** Apr. 14, 2020

- (54) **PORTION OF A DISPLAY PANEL WITH A GRAPHICAL USER INTERFACE**
- (71) Applicant: **GOOGLE INC.**, Mountain View, CA (US)
- (72) Inventors: **Shiva Jaini**, Santa Clara, CA (US); **Satoe Haile**, San Francisco, CA (US)
- (73) Assignee: **Google LLC**, Mountain View, CA (US)
- (**) Term: **15 Years**
- (21) Appl. No.: **29/607,333**
- (22) Filed: **Jun. 12, 2017**

Related U.S. Application Data

- (62) Division of application No. 29/518,263, filed on Feb. 20, 2015, now Pat. No. Des. 789,392.

CLAIM

The ornamental design for a portion of a display panel with a graphical user interface, as shown and described.

DESCRIPTION

The FIGURE is a front view of a portion of a display panel with a graphical user interface showing features of my new design.

The broken lines including the showing of a portion of a display panel of a communications terminal surrounding the illustrated graphical user interface and the portions of the graphical user interface are included for the purpose of illustrating environmental structure and form no part of the claimed design.

1 Claim, 1 Drawing Sheet
